[57] CLAIM

The ornamental design for a combined table and aquarium or the like, as shown and described.

DESCRIPTION

FIG. 1 is a perspective view of a combined table and aquarium or the like embodying my new design;

FIG. 2 is a top plan view thereof;

FIG. 3 is an elevational view taken from one side thereof, the opposite side being the same as the side shown;

FIG. 4 is an elevational view taken from one end thereof, the opposite end being the same as the end shown;

FIG. 5 is a perspective view of a modified form of the combined table and aquarium or the like shown in FIG. 1;

FIG. 6 is a top plan view of FIG. 5;

FIG. 7 is an elevational view taken from one side of FIG. 5, the opposite side being the same as the side shown;

FIG. 8 is an elevational view taken from one end of FIG. 5, the opposite end being the same as the end shown; and

FIG. 9 is a cross sectional view taken on line 7—7 of FIG. 7.
